CONTROLLED ENVIRONMENT PLANT GROWTH CABINET

Dan H. Walters, Marshall, Mich., assignor to Sherer-Gillett Company, a corporation of Illinois

Filed Mar. 16, 1964, Ser. No. 78,999

Term of patent 14 years

(Cl. D35—3)

FIG. 1

FIG. 2

FIG. 3

FIGURE 1 is a front perspective view of a controlled environment plant growth cabinet embodying my new design.

FIGURE 2 is a rear perspective view of same.

FIGURE 3 is a top view of the controlled environment plant growth cabinet shown in FIGURES 1 and 2.

The undisclosed side of the instant article shown in FIGURE 1 is substantially the same as the side shown, except as illustrated in FIG. 2.

I claim:

The ornamental design for a controlled environment plant growth cabinet, substantially as shown and described.
